US0D1069118S

(12) **United States Design Patent** (10) Patent No.: **US D1,069,118 S**
(45) Date of Patent: ** Apr. 1, 2025

(54) **IMPACTOR HANDLE WITH TIP ASSEMBLY**

(71) Applicant: **DEPUY IRELAND UNLIMITED COMPANY**, Ringaskiddy (IE)

(72) Inventors: **Graeme Dutton**, Worsthorne (GB);
Jamie Atkin, Chapelton (GB);
Prasenjit Saha, Leeds (GB)

(73) Assignee: **DEPUY IRELAND UNLIMITED COMPANY LOUGHBEG INDUSTRIAL ESTATE**, Ringaskiddy (IE)

(**) Term: **15 Years**

(21) Appl. No.: **29/835,705**

(22) Filed: **Apr. 21, 2022**

(51) LOC (15) Cl. **24-03**
(52) U.S. Cl. **USPC D24/155**

(58) **Field of Classification Search**

USPC D24/155, 133, 142, 147, 171
CPC A61B 17/92

Primary Examiner — Eliza Z Harvey

(57) **CLAIM**

The ornamental design for an impactor handle with tip assembly, as shown and described.

DESCRIPTION

FIG. 1: is a perspective view of the impactor handle showing the new, original and ornamental design;

FIG. 2: is a first side view thereof;

FIG. 3: is a second side view thereof;

FIG. 4: is a top view thereof; and,

FIG. 5: is a bottom view thereof.

The features shown in broken lines in various Figures are for illustrating reference or environmental structure.

1 Claim, 3 Drawing Sheets
